SPECIFICATION forming part of Design No. 26,210, dated October 20, 1896.

Application filed August 24, 1896. Serial No. 603,782. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of ornaments of lamp-like form, with ornamental scrolls diverging from the base of said ornaments, with small festoons hanging from said scrolls, and vertical stripes wound with spiral running ribbons, as represented in the accompanying drawing.

The border for said design is formed of upright torch-like ornaments connected at their base with said stripes wound with spiral running ribbons and festoons of ribbons hanging from said torch-like ornaments, as shown in the drawing.

What I claim is—

The design for wall-paper herein shown and described.

Witness my hand this 10th day of August, 1896.
